HANDBAG CLOSURE CLASP

Etienne Aigner, 217 Haven Ave., New York, N.Y.

Filed Dec. 12, 1960, Ser. No. 63,191

Term of patent 14 years

(Cl. D87—2)

FIG. 1.

FIG. 2.

FIG. 3.

FIG. 4.

FIG. 5.

FIG. 1 is a front elevational view of a handbag closure clasp, showing my new design;

FIG. 2 is a side elevational view thereof;

FIG. 3 is a rear elevational view thereof;

FIG. 4 is a front elevational view thereof, with the latch partially revolved; and

FIG. 5 is a sectional view taken on the line 5—5 of FIG. 4.

I claim:

The ornamental design for a handbag closure clasp, substantially as shown.
